LIGHTING APPARATUS

Lindsley Schepmoes, New Haven, Conn., assignor to The Safety Car Heating & Lighting Company, a corporation of New Jersey

Application April 2, 1935, Serial No. 14,266

18 Claims. (Cl. 240—7.35)

This invention relates to lighting apparatus.

One of the objects of this invention is to provide lighting apparatus which will be simple, practical and thoroughly durable. Another object is to provide apparatus of the above character characterized by efficiency in operation and ease of installation. Another object is to provide apparatus of the above character which may be easily manufactured with a minimum amount of labor and from inexpensive materials. Another object is to provide apparatus of the above character which may be installed in a room, vehicle, or the like, without altering materially or damaging in any way the original structure of the room or vehicle. Another object is to provide apparatus of the above character complete in itself and requiring no additional parts, as, for example, conductors in the walls of the room in which it is installed. Another object is to provide apparatus of the above character which provides maximum lighting efficiency while guarding against glare or other undesirable qualities. Another object is to provide apparatus of the above character which will give off an even intensity of illumination. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings, in which is shown one of the various possible embodiments of this invention,

Figure 1 is a side elevation of an electrical illuminator to be used with my apparatus;

Figure 2 is an end elevation of one of the reflector plates to be used in my apparatus;

Figure 3 is a side elevation of a portion of my apparatus as secured to a wall or the like, certain of the parts thereof being broken away;

Figure 4 is a vertical sectional view of another portion of my apparatus as secured to a wall or the like;

Figure 5 is a vertical sectional view of my apparatus taken along the line 5—5 of Figure 4;

Figure 6 is a vertical sectional view of my apparatus taken along the line 6—6 of Figure 4;

Figure 7 is a side elevational view of my apparatus as installed, certain portions thereof being broken away;

Figure 8 is a bottom plan view of the apparatus shown in Figure 7;

Figure 9 is a side elevational view of one of the intermediate sockets used in my apparatus;

Figure 10 is a side elevational view of one of the end sockets used in my apparatus;

Figure 11 is a bottom plan view of the base portion of the socket shown in Figure 9;

Figure 12 is a vertical sectional view taken along the line 12—12 of Figure 11;

Figure 13 is a vertical sectional view taken along the line 13—13 of Figure 11;

Figure 14 is an end elevation of the socket shown in Figure 9, and

Figure 15 is a top plan view of the socket shown in Figure 9.

Similar reference characters refer to similar parts throughout the several views of the drawings.

Referring first to Figure 7, my apparatus is there shown installed on a wall or the like and preferably comprises a series of elongated tubular electrical illuminators generally indicated at 10 supported in substantial alignment along the wall by end sockets generally indicated at 11 and intermediate sockets generally indicated at 12. Preferably the illuminators 10 are surrounded by 25 a plurality of spaced plate-like reflector members generally indicated at 13 whose planes are substantially perpendicular to the axes of the illuminators. The apparatus is so constructed that the various parts thereof are easily removable for purposes of repair or the like as will be more fully described hereinafter.

Turning now to Figure 1, there is shown one of the illuminators generally indicated at 10. These illuminators preferably comprise elongated tubular members 14 having metal end caps 15 at their opposite ends and a filament 16 running axially therethrough. Filament 16 is electrically connected with end caps 15 so that contact with the end caps may connect the illuminator in a circuit. Tubular members 14 may be formed from any suitable material, as, for example, glass, and I prefer to use a clear glass tube in my apparatus.

As best shown in Figures 4 and 5, my apparatus may be installed at any point in a room or the like as to the ceiling or wall generally indicated at 17. Thus there is provided a plate generally indicated at 18 secured to the wall by screws or the like generally indicated at 19 which may be substantially equal in length to the length of my apparatus on any particular wall or ceiling, or in other instances, may be divided into individual sections secured to the wall in end to end relation. As more clearly shown in Figure 5, the longitudinal edges 20 of plate 18 rest against

the wall 17 whereas the intermediate portion thereof is preferably suspended below the wall. Formed within plate 18 is a pair of longitudinal channels 21 and 22 bordering a central portion 23 which is preferably flat.

Plate 18 has secured thereto sockets 11 and 12 preferably mounted in alignment along portion 23 thereof and preferably regularly spaced from each other in order to receive therebetween a series of illuminators 10 of standard length.

Socket 12 may be formed from any suitable composition having electrical insulating qualities, as, for example, bakelite. As best shown in Figures 9 and 11-15, this socket comprises a base portion 24 and a cylindrical portion 25 mounted thereon. Base portion 24 has formed in its bottom side longitudinal channels 26 and 27 (Figure 11), channel 27 connecting with an indentation 28. Base portion 24 is also provided with a pair of apertures 29 and 30 for the reception of fastening screws as will be more clearly described hereinafter.

Indentation 28 is located substantially above cylindrical portion 25 which has an annular ridge 31 formed in its inner surface and substantially dividing it in half. A spring contact part generally indicated at 32 is disposed within cylindrical portion 25 and preferably comprises sections 33 and 34 joined at its base 35 so that it is substantially U-shaped as viewed in the section shown in Figure 13. Contact part 32 is preferably formed from resilient metallic material and disposed immediately beneath its base 35 is a fastening block 36 preferably running throughout the width of the contact part. A rivet 37 is secured to block 36 and extends through base portion 24 and into indentation 28. The end of rivet 37 is headed over on a contact plate 38 (Figure 13) in indentation 28, this plate having a screw 39 threaded therein substantially opposite channel 27.

As best shown in Figures 12 and 15, cylindrical portion 25 is cut away to provide an opening 40 running from a point near the bottom of the cylindrical portion substantially to base 24 and from the edge of the cylindrical portion substantially to annular ridge 31. Similarly, section 34 of contact part 32 is open at this point (Figure 12) so that section 34 is substantially U-shaped. On the other hand, section 33 of contact part 32 is substantially circular in shape and has formed therein a central aperture 41 (Figures 13 and 14). As best shown in Figure 4, socket 12 may be connected to plate 18 by way of screws generally indicated at 42.

The construction of socket 11 is somewhat similar to that of socket 12. Thus socket 11 has a base portion 43 (Figure 10) having formed in its bottom side longitudinal channels generally indicated at 44 similar in shape and position to channels 26 and 27 (Figure 11), one of these channels connecting with an indentation 45 (Figure 3). As better shown in Figure 3, a cup portion 46 is secured to base 43 having disposed therein a contact part generally indicated at 47 substantially similar in construction to contact part 32 (Figure 13). Thus contact part 47 is provided with a substantially circular portion 48 having an aperture 49. In section, as viewed in Figure 3, contact part 47 is substantially U-shaped, the base thereof having a block 50 resting thereupon and connected with a rivet 51 extending through base 43 into indentation 45. Rivet 51 is headed over on a contact plate 52 in which

is threaded a screw 53 whose position is substantially similar to screw 39 (Figure 12).

Cup portion 46 (Figure 3) has a shoulder 54 formed therein against which section 55 of contact part 47 rests. Base 43 is secured to plate 18 (Figure 3) by screws generally indicated at 56. For a purpose to be more fully described hereinafter, I prefer to secure a substantially circular and translucent plate member 57 to socket 11 by way of a screw 58, this plate extending to ceiling 17 and being preferably similar in circumferential dimensions to plates 18.

As best shown in Figures 7 and 8, sockets 11 and 12 are so arranged along plate 18 that opening 40 is opposite either sockets 11 or sections 25a (Figure 13) of socket 12. Accordingly illuminators 10 may be easily inserted in pairs of sockets. For example, one end of an illuminator 10 may be inserted in cup 46 of socket 11 so that portion 15a of cap 15 (Figure 1) fits within aperture 49 of contact part 47, the circular portion 48 thereof resting flush against the outer portion of the cap. Next, the other end of the illuminator may be slipped through opening 40 in a socket 11 (Figure 7) so that portion 15a of the 25 cap slips into the opening in section 34 of contact part 32. Section 35 thus rests against the outer portion of cap 15 about portion 15a thereof to form a good electrical contact therewith. It will thus be seen that the insertion or removal of the illuminators 10 from the sockets 11 and 12 may be accomplished with ease and does not require any tools or intricate operations.

Reflector plates 13 may be formed from any suitable material, preferably opaque in character. 35 They are here shown as die cast although in certain instances I prefer to make them from sheet metal or the like. As best shown in Figure 2, plates 13 are substantially circular in shape having indentures 59 so that they may fit about the 40 individual illuminators as will be more fully described hereinafter. Formed in the sides of plates 13 opposite indentures 59 are holes 60 and 61, all as best shown in Figure 2.

Reflector plates 13 are preferably grouped in 45 units, each unit of reflectors being designed to fit between two of the sockets and surround one of the illuminators 10. Thus several of the reflectors 13 are held in position between one end socket 11 and a socket 12 by a pair of bars generally indicated at 62 (Figures 7 and 8) while a group of reflectors 13 positioned between two of sockets 12 may be held in their allotted position by a pair of bars generally indicated at 63. These units of reflector plates 13 are of standard length 50 due to the standard distance between the sockets 12 and 11 and the sockets 12. Inasmuch as their construction and size are substantially similar, one only will be described in detail.

Bars 62 extend through holes 60 and 61 (Figure 60 2) and the reflectors are preferably regularly spaced along the bars. Although the reflectors may be secured to bars 62 in any convenient manner, I prefer to thread a plurality of nuts generally indicated at 64 on the bars, these nuts 65 being grouped in pairs one on each side of each reflector plate 13 to hold the reflector plates in their allotted position. Although reflectors 13 may be spaced along the bars 62 any convenient distance, I prefer to so space them that a line 70 drawn from the periphery of one of them to the junction of the next succeeding reflector and the illuminator is at an angle of approximately 50° to the axis of the illuminator. Bars 62 when in position within holes 60 and 61 (Figure 2) are 75

spaced from each other a sufficient distance to lie above channels 21 and 22 (Figures 5 and 6) and nuts 64 are preferably round in shape so that they may rest within the channels 21 and 22 to support the bars in this position.

Bridging the space between the respective bases of the sockets are a plurality of cover plates generally indicated at 65 as best shown in Figures 4, 5, and 8. Cover plates 65 are substantially U-shaped in cross-section, as best shown in Figure 5, thus having their opposite edges resting upon flat portion 23 of plate 18 and are secured in this position by a plurality of screws generally indicated at 66 (Figure 4). Accordingly these cover plates enclose the space between each of the sockets and are conveniently situated for carrying conductors generally indicated at 67 which must of necessity run between the sockets. Thus the conductors may be connected to screws 39 and 53 as desired to achieve the desired circuit and run through channels 26 and 27 of the sockets 11 as well as channels 44 of sockets 12 (Figures 10 and 11) thus to achieve an independent electrical connection between these various parts without any outside wiring. It is to be particularly noted that in this manner the wiring for my entire lighting system may be contained within the apparatus and it therefore becomes unnecessary to run wires through the walls or ceiling 17 to which the apparatus is secured.

Rotatably connected to cover plates 65, as best shown in Figure 8, is a plurality of clip members generally indicated at 68 of sufficient length to extend over bars 62 and 63 when in a right angle position with respect to the axes of illuminators 10 as will be more fully described hereinafter. Thus a clip member 68 shown in Figure 5 preferably has a pin 69 extending therethrough and through cover plate 65 into the interior thereof. Pin 69 is provided with a head 70 and disposed between head 70 and the top of cover plate 65 is a spiral spring 71 serving to continually force clip member 68 against the top of cover plate 65 and hence against the bars 62. Accordingly when clip members 68 are rotated so that the ends thereof are out of engagement with the bars, the bars are free to drop from plate 18, but when they are rotated into the position shown in Figures 5 and 8, they serve to hold the bars firmly against the cover plate. Furthermore, due to the pressure exerted by the spring member 71, the nuts on the bars are held firmly against the cover plate against relative vibration.

As noted above, pairs of bars and groups of reflectors 13 make up individual units to be placed between pairs of sockets. In order to safeguard further against glare, I prefer in some instances to provide each of these units with an additional shade or the like comprising a translucent strip generally indicated at 72 secured to the indentures 59 of reflectors 13 and in substantial alignment with illuminators 10. Strips 72 may be secured to the reflectors in any convenient manner this depending upon the characteristics of the reflector plate used. In this instance the strips may be connected to the reflector plates by screws generally indicated at 73 threaded into the reflectors.

It will now become clear that the units to be disposed between the various sockets comprise pairs of bars such as bars 62 or bars 63 having secured thereto a suitable number of reflectors 13 and a strip 72. In order to assemble the apparatus, an illuminator 10 is inserted in a

socket having a continuous end, as, for example, section 25a of socket 12 (Figures 7 and 8). Next the illuminator is moved longitudinally against the spring pressure of contact part 32 (Figure 4), portion 15a of cap 15 of the illuminator fitting 5 within aperture 41 of the contact part. The free end of illuminator 10 may then be slipped through opening 40 of another socket 12 and thence into position in contact with portion 34 of its contact part 32 (Figure 4). The illuminator is now in 10 position and ready for use.

Next, one of the reflector units is placed in position over the illuminator. Clip members 68, between the two sockets in which the illuminator has been inserted, are moved over the cover plates 15 so that the bars may be brought down upon plate 18, the illuminator being located within the indentures 59 of reflector plates 13. After this, the clip members 68 are given a half turn to extend over the bars 62 or 63 of the unit to hold 20 the reflector unit in assembled relation. The apparatus is then in position for operation and, of course, the remaining units may be assembled or disassembled in a like manner.

When in this assembled position, strips 72 25 (Figures 3 and 8) lie substantially in front of illuminators 10 so that the line of vision of a person looking at the apparatus will not directly contact the filament in the illuminators. Of course the position of strips 72 with respect to 30 the illuminators may be varied according to the position which the apparatus is to occupy so that these strips prevent undue glare when glanced at from any normal position of an occupant of the room.

It should be particularly noted that it is very easy to remove the individual units for purposes of repair by merely rotating the clip members 68 and pulling one end of the illuminators from one of the sockets. If it becomes necessary to 40 examine the wiring of the apparatus for any reason, it is a simple matter to remove cover plates 65 to expose the wiring, this factor having a marked advantage over many common systems of lighting where, under such circumstances, it 45 is necessary to rip out portions of the wall, ceiling, or the like. The entire design of the apparatus lends itself to a structure which may be achieved from light and inexpensive materials which are easy to work during manufacture and 50 which are more desirable for use in modern building of any sort.

It will thus be seen that I have provided a practical, efficient, and thoroughly durable apparatus in which the several objects hereinabove mentioned as well as many others are successfully accomplished.

As many possible embodiments may be made of the above invention and as many changes 60 might be made in the embodiment above set forth, it is to be understood that all matter hereinbefore set forth or shown in the accompanying drawings is to be interpreted as illustrative and not in a limiting sense.

I claim:

1. In lighting apparatus, in combination, a ceiling, a base member secured to said ceiling, a plurality of socket members secured to said base member at spaced intervals therealong, a 70 plurality of longitudinal light bulbs disposed within said socket members and bridging the space therebetween, a plurality of plate-like reflectors adapted to fit about said bulbs, and means movably secured to said base member for 75

detachably holding said reflectors to said base member at spaced points along said bulbs.

2. In lighting apparatus, in combination, a ceiling, a base member secured to said ceiling, a plurality of socket members secured to said base member at spaced intervals therealong, a plurality of longitudinal light bulbs disposed within said socket members and bridging the space therebetween, a plurality of plate-like reflectors adapted to fit about said bulbs, an elongated member secured to said base member, said reflectors being secured to said elongated member for holding said reflectors as a unit to said base member at spaced points along said bulbs, said socket members holding said bulbs in substantial alignment, and means for detachably mounting said unit in related assembly with said light bulbs.

3. In lighting apparatus, in combination, a ceiling, a base member secured to said ceiling, a plurality of socket members secured to said base member at spaced intervals therealong, a plurality of longitudinal light bulbs disposed within said socket members and bridging the space therebetween, a plurality of plate-like reflectors adapted to fit about said bulbs, means for holding said reflectors to said base member at spaced points along said bulbs said means being detachable whereby said reflectors may be removed without disturbing said bulbs, said socket members adapted to hold said bulbs in substantial alignment, said socket members having base members with longitudinal channels formed therein, and a plurality of channel parts fitting between the respective base members of said sockets and having their open sides resting upon said base members to enclose electrical conductors running to said socket members.

4. In lighting apparatus, in combination, a base, a plurality of socket members secured to said base at spaced points therealong, said socket members being in substantial alignment, a plurality of tubular electrical illuminators disposed within said socket members and bridging the space therebetween, means disposed within said socket members for achieving an electrical contact with said illuminators, pairs of spaced bars detachably secured to said base, each pair being located between two of said socket members, and a plurality of plate-like reflectors secured to said bars at spaced points therealong.

5. In lighting apparatus, in combination, a base, a plurality of socket members secured to said base at spaced points therealong, said socket members being in substantial alignment, a plurality of tubular electrical illuminators disposed within said socket members and bridging the space therebetween, means disposed within said socket members for achieving an electrical contact with said illuminators, pairs of spaced bars detachably secured to said base, each pair being located between two of said socket members, said bars being threaded, a plurality of nuts on said bars, and a plurality of plate-like reflectors secured to said bars at spaced intervals by pairs of said nuts.

6. In lighting apparatus, in combination, a base, a plurality of socket members secured thereto at spaced points therealong, said socket members being in alignment and having base portions, said base portions having longitudinal channels formed therein, contact members secured within each socket member and extending through said base portion to one of said channels,

a plurality of longitudinal cover plates bridging the space between each of said base portions and resting upon said base to enclose conductors running between said socket members, said cover plates being secured to said base, pairs of spaced bars, each bar bridging the space between respective pairs of socket members, a plurality of reflector plates secured to said bars, a plurality of electrical illuminators disposed within respective pairs of socket members and bridging the space therebetween, said reflectors having apertures through which said illuminators extend, and means for detachably securing said bars to said base.

7. In lighting apparatus, in combination, a base, a plurality of socket members secured thereto at spaced points therealong, said socket members being in alignment and having base portions, said base portions having longitudinal channels formed therein, contact members secured within each socket member and extending through said base portion to one of said channels, a plurality of longitudinal cover plates bridging the space between each of said base portions and resting upon said base to enclose conductors running between said socket members, said cover plates being secured to said base, pairs of spaced bars, each bar bridging the space between respective pairs of socket members, a plurality of reflector plates secured to said bars, a plurality of electrical illuminators disposed within respective pairs of socket members and bridging the space therebetween, said reflectors having apertures through which said illuminators extend, and means for detachably securing said bars to said base, said socket members having cylindrical portions within which the ends of said illuminators fit and openings in the sides thereof so that said illuminators may be inserted or removed in sidewise directions with respect to the axes of said illuminators whereby said illuminators may be removed for repair.

8. In lighting apparatus, in combination, a base, a plurality of socket members secured thereto at spaced points therealong, said socket members being in alignment and having base portions, said base portions having longitudinal channels formed therein, contact members secured within each socket member and extending through said base portion to one of said channels, a plurality of longitudinal cover plates bridging the space between each of said base portions and resting upon said base to enclose conductors running between said socket members, said cover plates being secured to said base, pairs of spaced bars, each bar bridging the space between respective pairs of socket members, a plurality of reflector plates secured to said bars, a plurality of electrical illuminators disposed within respective pairs of socket members and bridging the space therebetween, said reflectors having apertures through which said illuminators extend, and a series of fastening parts pivotally connected to said cover plates and adapted to extend over said bars to secure said bars to said base.

9. In lighting apparatus, in combination, a wall, a plurality of elongated electrical illuminators, means for mounting said illuminators on said wall in continuous end to end alignment, and a plurality of disk-like reflector parts detachably secured to said wall at spaced points therealong and adjacent said illuminators, the planes of said reflector parts being substantially at right angles to said wall, said reflectors being removable from

their installed position without disconnecting or removing said illuminators.

10. In lighting apparatus, in combination, a supporting surface, an elongated channel member secured to said surface, an illuminating element secured to said surface adjacent said channel member, electric conductors disposed in said channel member and connected to said illuminating element, securing means attached to said channel member, and a plurality of reflectors adapted to fit about said illuminating element and secured to said securing means, said reflectors lying in parallel planes normal to the axis of said channel member.

15. 11. In lighting apparatus, in combination, a supporting surface, an elongated channel member secured to said surface, an illuminating element secured to said surface adjacent said channel member, electric conductors disposed in said channel member and connected to said illuminating element, an elongated member secured to said channel member, and a plurality of plate-like reflectors adapted to fit about said illuminating means and attached to said elongated member, said reflectors lying in parallel planes normal to the axis of said channel member.

20. 12. In lighting apparatus, in combination, a supporting surface, an elongated channel member secured to said surface, an illuminating element secured to said surface adjacent said channel member, electric conductors disposed in said channel member and connected to said illuminating element, an elongated member, a plurality of plate-like reflectors adapted to fit about said illuminating means and attached to said elongated member, and means for detachably securing said elongated member to said channel member, whereby said reflectors and said elongated member may be readily attached to or detached from said channel members as a unit.

25. 13. In lighting apparatus, in combination, a support, an elongated substantially U-shaped channel member secured to said support, an elongated illuminator secured to said support adjacent said channel member, electric conductors disposed in said channel member and connected to said illuminator, a pair of bar members, a plurality of plate-like reflectors secured to said bar members in spaced relationship whereby said

reflectors comprise a unit adapted to fit about said illuminator, and means for securing said unit to said channel member.

14. In lighting apparatus, in combination, a support, an elongated illuminator secured to said support, a plurality of spaced reflectors secured together as a unit and disposed about said illuminator, and means for securing said unit to said support, said means including a spring-biased clip operable to detachably secure the unit to the support.

15. In lighting apparatus, in combination, a wall, a plate secured to said wall, a plurality of sockets secured to said plate, elongated illuminators each having an end mounted in adjacent pairs of sockets, supporting members secured to said plate between adjacent pairs of sockets, and reflector units disposed about said illuminators and secured to said supporting members.

20. 16. In lighting apparatus, in combination, an elongated light source, means for directing the rays emanating from said light source substantially at right angles to the axis of said light source, said means including parts detachably associated as a unit with said light source, and means engageable at will with said unit for maintaining it in related assembly with said light source.

25. 17. In lighting apparatus, in combination, a horizontal elongated light source for emanating light rays radially therefrom, means for directing the rays emanating from said light source substantially at right angles to the axis of said light source, and means associated with said first-mentioned means for obstructing some of said light rays.

30. 18. In lighting apparatus, in combination, a support, an elongated channel member secured to said support, an elongated illuminator secured to said support adjacent said channel member, electric conductors disposed in said channel member and connected to said illuminator, a plurality of plate-like reflectors, each of which has a substantially U-shaped slot formed therein, an elongated part secured to said reflectors to mount said reflectors as a unit adapted to fit about said illuminator, and means for securing said unit to said channel member.

LINDSLEY SCHEPMOES.
